UNITED STATES PATENT OFFICE.

FRANCIS W. TULLY, OF BROOKLINE, MASSACHUSETTS.

WINDOW-CLEANING APPARATUS.

Application filed April 6, 1920. Serial No. 371,714.

To all whom it may concern:

Be it known that I, FRANCIS W. TULLY, citizen of the United States of America, and resident of Brookline, in the county of Norfolk and State of Massachusetts, have invented new and useful Improvements in Window-Cleaning Apparatus, of which the following is a specification.

My invention relates to apparatus for cleaning windows and the like, and has for its objects, among other things, the provision of portable and easily manipulated means for cleaning surfaces such as those of windows, rapidly and safely, and with a minimum of cleaning liquid; the provision also of means for absorbing from the cleaned surface the cleaning liquid and dirt collected thereby in the shortest possible time after said liquid has performed its cleaning function. A variety of useful results are obtainable by the employment of apparatus embodying my invention, according to the situation in and the conditions under, which, it is used. The outside surfaces of windows can be cleansed by means of this apparatus without obliging the operator to sit or stand on the window ledge outside; in cold weather my improved cleaning apparatus absorbs and removes the cleansing liquid before it has had time to freeze. Because of the fact that this apparatus employs the minimum amount of liquid necessary to effect cleansing of the window, or similar surface, it can be used to clean the inner surfaces of glazed show cases without removing or disturbing their contents.

Other adaptabilities and utilities of these improvements will transpire in the course of the following description of an example of such apparatus.

In the drawings hereto annexed, which illustrate an embodiment of my invention;

Figure 1 is a side elevation of the window cleaner, in the position it will occupy while operating on a vertical surface;

Figure 2 is a cross section through the operating parts of the apparatus, taken at the line 2-2 of Fig. 3;

Figure 3 is a view in elevation of the working face of the window cleaner; and

Figure 4 is a side elevation (partly broken away) as viewed from the lower side of Figure 3.

The example here shown for illustration comprises a holder which includes a base 1, a shaft-journal portion 2, and hollow pe-

ripherally disposed posts 3. The stub-shaft 7 is journaled in the journal portion 2, and flexible driving means 8, suitably housed in a flexible tube 9, is connected to the stub-shaft 7.

Fingers 4 are mounted in the hollow posts 3, and are yieldingly sustained by springs 5. Each of the fingers 4 is tipped at 6 with soft material, such as rubber, which is well adapted to make contact with a window surface.

A tank 10, provided with a suitable filling-opening 10^a is keyed or otherwise secured to the stub-shaft 7, and is thus mounted to rotate on the holder. To this tank the operating members of the window cleaner are secured. These comprise a scrubber and a drier. The scrubber is adapted to carry water or other cleansing fluid to, and to spread it on, the window surface; the drier is adapted to wipe the fluid from the surface and to absorb and dry it.

In the example here illustrated, the scrubber comprises fluid applying means, preferably, the wick 13, supplying fluid to the applying surface by capillarity, and sustained by the saddle 12 mounted on posts 11, and housed by the walls 18, and fluid spreading means, namely; the flexible strips or "squeegees" 19, held between the walls 18 and clamping plates 20. The squeegees or spreaders 19 will preferably be made of rubber; though leather will serve. The drier here shown consists of strips 14 of cloth, felt, or chamois-leather, held in assemblage between convoluted metal strips 15, 16. These strips are secured by pivot pins 23 and screws 24 to ears 21 and 22 which project from the clamping plates 20, and are also steadied by engagement with posts 25 mounted on the side 17 of the tank 10.

The scrubber members, i. e. wick 13 and spreaders 19 preferably extend diametrically across the rotary member, i. e., tank 10; while the drier members, i. e., felt or soft absorbent leather strips 14 surround the scrubber. By disposing the drier in convolutions, a relatively large quantity of wiping and absorbing material is provided.

The clamping plates 20 are secured in position by disengageable means, such as the eye-bolts 26 and wing-nuts 27. The outer strips 16 are pivoted at 23, and held at the other ends by screws 24, which pass through the eyes 16^a. By removing a screw 24, the strip 16 can be swung outwardly—as sug-

gested by the dotted line position of the strip in Fig. 3—and the drier-material 14 removed to be washed, or reversed, when necessary.

The operating surfaces of the scrubber 5 and drier are in substantially the same plane, so that when the rotary member (the tank 10 in the illustration here shown) is rotated, as by flexible shaft 8, the performance of the respective scrubbing, wiping, and drying functions is simultaneous.

For facility in handling the above described apparatus, the handle 29 is provided. This is pivotally secured to the journal extension 2 of the holder at 28, and is steadied by means of the curved arm 30, which passes through the handle 29 at 33. Springs 31 and 32 surround the arm 30, and abut, respectively, against the holder 1 and nut 34. Both these springs normally exert pressure against the handle 29, which is thus held in yielding relation to the holder 1.

The operation of the above described apparatus is as follows:

The tank 10 having been filled with water or other cleansing fluid, and the aperture 10¹⁰ being closed, the person operating the apparatus takes it by the handle 29 and brings the tips 6 of the yielding fingers 4 to bear on the surface to be cleaned, and sets the rotary member—i. e. tank 10,—with the operating factors carried thereby into rapid rotation by starting a motor (not shown) which is conveniently attached to the flexible shaft 8. The capillary action of the wick 13, which serves as the liquid applying means, draws the cleansing fluid from the tank 10 and deposits it on the surface to be cleaned, wetting an area swept by the face of the wick as it rotates. The squeegee-strips 19 spread the fluid over the surface, aiding the fluid to start the dirt. The wipers and driers 14 absorb the liquid and pick up the dirt; thus the wetting, spreading, wiping and drying go on simultaneously. The operator traverses the apparatus over the surface to be cleaned, so that all parts of the surface are subjected to the action of the above described operating factors.

Very little water or other cleansing fluid is actually required to remove a film of dust, such as collects on glass surfaces, and an adequate amount for the purpose is supplied by the capillary action of the liquid supplying means here described. Preferably, only the minimum of fluid required, will be supplied; a surplus, however, will do no harm in most instances. But in very cold weather, it is desirable to wipe and dry a window pane promptly after the application of water, and to use as little water as possible, in order to avoid the formation of ice. Also, if show cases and the like are to be cleaned, the minimum necessary quantity of water for cleansing purposes can be immediately absorbed by the above described ap-

paratus, which can be used, therefore, without necessitating the removal of articles on exhibition in the show case. It is obvious from the foregoing description that the cleaning apparatus can conveniently be employed in places difficult to reach with ordinary appliances. Moreover the above-described apparatus is in large measure self-cleaning. If, while cleaning a window the holder be removed from the glass, the reduction of load on the motor will speed up the rotation of the tank 10 and the cleaning instruments carried by it, and the water and dirt will be centrifugally flung out of the wiper pads 14.

The principle on which the cleaning apparatus operates is, as described in detail above, the simultaneous action of a scrubber and drier in close juxtaposition; this is effected by having the operating faces of these two factors in substantially the same plane; also, the application and spreading of cleansing fluid from a center outward to the drier; this is effected by locating the scrubber inside the drier.

While means for affording a more copious supply of cleansing fluid than the capillary wick might be employed, the capillary wetting means is preferred, since it is economical and supplies enough for effective work. The wick, as arranged in the apparatus herein described, itself performs a part of the spreading and scrubbing function, and might be employed without any auxiliary scrubbers such as the squeegee strips. These, however, are to be recommended, for, not only do they assist materially in spreading the fluid, but they also give the surface a wet wipe, and relieve the face of the wick from frictional abrasion.

I claim:

1. A window cleaner comprising in combination a scrubber and a drier, having their respective operating surfaces in substantially the same plane and normally fixed relatively to one another, means for supplying washing liquid to the scrubber, means simultaneously to move the scrubber and drier while in contact with a window surface, and a handle whereby said scrubber and drier may be manipulated.

2. A window cleaner comprising in combination a scrubber, a drier surrounding the scrubber, the operating surfaces of the scrubber and drier lying in substantially the same plane, means to supply washing liquid to the scrubber and means to rotate the scrubber and drier simultaneously on a window surface.

3. A window cleaner comprising in combination, a scrubber and a drier having their respective operating surfaces lying in substantially the same plane and fixed relatively to one another, capillary means to supply washing liquid to the scrubber, and

power actuated means simultaneously to move the scrubber and drier while in contact with a window surface.

4. In a window cleaner, the combination of a scrubber comprising liquid supplying means and liquid spreading means, a drier, the operating surfaces of scrubber and drier respectively being arranged in substantially the same plane and fixed relatively one to the other, and means simultaneously to move the scrubber and drier while in contact with a window surface.

5. In a window-cleaner, the combination of a scrubber, comprising liquid applying means and liquid spreading means, a drier surrounding the scrubber, the operating surfaces of the scrubber and drier, respectively, lying in substantially the same plane, and means to rotate the scrubber and drier simultaneously on a window surface.

6. In a window cleaner, the combination of a scrubber comprising liquid-applying means, liquid-supplying means and liquid-spreading means, a drier, the operating surfaces of the scrubber and drier respectively lying in substantially the same plane and being fixed relatively to one another, and means simultaneously to move the scrubber and drier and while in contact with a window surface.

7. A window cleaner comprising in combination a scrubber, drying means surrounding the scrubber, the scrubber and drying means having their respective surfaces normally arranged in substantially the same plane, means for supplying cleaning liquid to the scrubber, and means for rotating the drier while the scrubber and drier simultaneously contact with a window surface.

8. A window cleaner comprising in combination a rotatable support, a scrubber, drying means mounted upon the support, the drying means being disposed radially outward beyond the scrubber as respects the axis of the support, the operating surfaces of the scrubber and drying means lying in substantially the same plane, means to supply washing fluid to the scrubber, and means connected with the rotating support for rotating the latter while the scrubber and drying means simultaneously contact with a window surface.

9. A window-cleaner, comprising in combination a scrubber and a drier, having their respective operating surfaces in substantially the same plane, said scrubber and drier being rotatable about a common axis, means to supply washing liquid to the scrubber and flexible drive means for simultaneously rotating said drier and scrubber.

10. In a window cleaner the combination of a rotating support having a fluid containing cavity therein, a scrubber mounted upon the support, and having spreading means, a drier surrounding the scrubber,

the operating surfaces of the scrubber, spreader and drier respectively lying in substantially the same plane, and flexible means to rotate the scrubber while in contact with a window surface.

11. A window cleaner, comprising in combination a holder, a handle therefor, a tank for liquid, rotatively mounted in the holder, a scrubber and a drier, mounted on the tank, the scrubber comprising capillary liquid supplying means in communication with the interior of the tank, the drier surrounding the scrubber, the operating surfaces of the scrubber and drier, respectively, lying in substantially the same plane, and means to rotate the tank with the attached scrubber and drier simultaneously on a window surface.

12. A window cleaner, comprising in combination a holder, a handle therefor, a tank for liquid, rotatively mounted in the holder, a scrubber and a drier, mounted on the tank, the scrubber comprising capillary liquid supplying means in communication with the interior of the tank, and liquid spreading means adjacent to the liquid supplying means, the drier surrounding the scrubber, the operating surfaces of the scrubber and drier, respectively, lying in substantially the same plane, and flexible means to rotate the tank with the attached scrubber and drier simultaneously on a window surface.

13. A window cleaner, comprising in combination a holder, a handle yieldingly attached to the holder, a tank for liquid, rotatively mounted in the holder, a scrubber and a drier mounted on the tank, the scrubber comprising capillary liquid supplying means in communication with the interior of the tank, the drier surrounding the scrubber, the operating surfaces of the scrubber and drier, respectively, lying in substantially the same plane, and means to rotate the tank with the attached scrubber and drier simultaneously on a window surface.

14. A window cleaner, comprising in combination, a holder, a handle yieldingly attached to the holder, a tank for liquid, rotatively mounted in the holder, a scrubber and a drier mounted on the tank, the scrubber comprising capillary liquid supplying means in communication with the interior of the tank and liquid spreading means adjacent to the liquid supplying means, the drier surrounding the scrubber, the operating surfaces of the scrubber and drier, respectively, being arranged in substantially the same plane, and means to rotate the tank with the attached scrubber and drier simultaneously on a window surface.

15. A window cleaner comprising in combination a holder, a handle for the holder, a support rotatably mounted upon

- the holder, a scrubber, a drier mounted upon the support and surrounding the scrubber, the drier being of convoluted outline, the operating surfaces of the scrubber and drier respectively lying in substantially the same plane, means to supply fluid to the scrubber, and means to rotate the support with the drier mounted thereon.
10. 16. A window cleaner comprising in combination a holder, yielding fingers on the holder adapted to rest against a window surface, a handle for the holder, a support rotatably mounted on the holder, a scrubber mounted upon the support, capillary means for supplying fluid to the scrubber, liquid spreading means mounted upon the support at a point adjacent to the liquid supplying means, a drier surrounding the scrubber, the operating surfaces of the scrubber, spreading means, and drier respectively lying in the same plane, and means to rotate the support with the attached scrubber and spreader.
15. 17. A window cleaner comprising in combination a holder, positioning fingers on the holder adapted to rest against a window surface, a handle pivotally attached to the holder, yielding means for retaining the holder and handle in normal relationship, a scrubber and drier carried by the holder, and means for simultaneously operating the scrubber and drier while the fingers are held in contact with a window surface.
20. 18. A window cleaner comprising in combination a holder, yieldingly mounted positioning fingers on the holder adapted to rest against a window surface, a handle pivotally attached to the holder, a scrubber, a spreader and a drier carried by the holder, means for supplying fluid to the scrubber, and means for rotating the drier about the axis of the holder while maintaining the fingers in contact with a window surface.
25. 19. In a window cleaner, the combination of a holder, a rotary member journaled in the holder, a scrubber and drier mounted on the rotary member, with their operating faces in substantially the same plane, the scrubber extending diametrically across the rotary member and the drier disposed on either side of the scrubber, means to supply cleaning liquid to the scrubber, and means to rotate the rotary member.
30. 20. A window cleaner comprising a holder having an axial bearing opening, a shaft journalled in said opening, a support mounted upon one end of said shaft, yielding positioning fingers projecting from the holder and spaced at substantially equal distances about the axis of said shaft, scrubbing and drying means carried by the support and simultaneously operable for cleaning a window, and means connected with the other end of the shaft for rotating it.
35. 21. In a window cleaner, the combination of a holder, a rotary member journaled in the holder, a scrubber and drier mounted on the rotary member with their operating faces in substantially the same plane, the scrubber comprising capillary means for supplying and means for spreading cleaning liquid and extending diametrically across the rotary member, and the drier disposed on either side of the scrubber, and means to rotate the rotary member.
40. 22. In a window cleaner the combination of a holder, a rotary member journalled in the holder, a drier of absorbent material mounted upon the rotary member, and means for removably securing the drier to the rotating member comprising separable clamping elements between which the drier may be secured, and releasable means for holding said clamping elements in operative relationship.
45. 23. A window cleaner comprising a rotatable support, a clamping strip mounted thereon, a second clamping strip normally parallel to the first strip, said second strip being pivotally supported at one of its ends to swing away from the other strip, releasable means engageable with the other end of the strip for holding the second clamping strip in operative relationship to the first strip, and a drier element normally clamped between said strip and engageable with a window surface for removing moisture therefrom.
50. Signed by me at Boston, Massachusetts, this second day of April, 1920.
- FRANCIS W. TULLY.
